UNITED STATES PATENT OFFICE.

MILES B. COOPER, OF PORTSMOUTH, OHIO.

ARCH-SUPPORT CONSTRUCTION.

Application filed June 19, 1922. Serial No. 569,389.

To all whom it may concern:

Be it known that I, MILES B. COOPER, a citizen of the United States, residing at Portsmouth, in the county of Scioto and State of Ohio, have invented certain new and useful Improvements in Arch-Support Constructions, of which the following is a specification, reference being had therein to the accompanying drawing.

10 This invention relates to an improvement in the construction of shoes and has special reference to an inner sole and arch support used in connection with the inner sole. One object of the invention is to so construct the inner sole and arch support that the instep portion of the foot may be braced and the arch portion of the foot so supported that a person suffering from a fallen arch may have the instep and arch portion of the foot supported and the fallen arch forced back into the proper position.

20 Another object of the invention is to so construct the inner sole and arch support that the instep and arch portion of the foot will be not only supported but will also be positioned between side wings of the inner sole and a reinforcing plate and thus held against spreading.

25 Another object of the invention is to so construct the inner sole and bracing and padding means that this improved construction may be embodied in connection with a shoe of a conventional construction without causing the shoe to lose its ordinary appearance.

30 Another object of the invention is to so construct this improved inner sole and arch support that it will be very comfortable to wear in the shoe and further so constructed that it will not readily slip out of place.

35 This invention is illustrated in the accompanying drawings, wherein:

40 Figure 1 is a view showing a shoe partially in side elevation and partially in section and having the improved inner sole and arch support construction.

45 Figure 2 is a top plan view of a sheet metal plate which constitutes the main bracing and supporting element.

50 Figure 3 is a view showing the plate in side elevation.

55 Figure 4 is a top plan view of a pad positioned beneath the instep of the foot.

Figure 5 is a view showing the pad of Fig. 4 in side elevation.

Figure 6 is a view showing the pad of Fig. 4 in end elevation.

Figure 7 is a view showing the inner sole in side elevation.

Figure 8 is a top plan view of the inner sole.

Figure 9 is a top plan view of an inner sole section which is to be mounted beneath the heel and instep portion of the inner sole shown in Fig. 7.

Figure 10 is a view showing the structure of Fig. 9 in side elevation.

This improved construction has been shown illustrated in connection with a shoe which is of a conventional construction and provided with the usual upper U, sole S and heel H. It will be understood that the shoe shown simply illustrates one specific construction of shoe with which the structure may be embodied and that this improved construction may be embodied in connection with any shoe for which it is suited. The inner sole 1 is of the proper size and shape to fit into the shoe. The ball portion of this insole 1 is channeled as shown at 2 and the

instep portion is provided with side wings 3, one of which is to be positioned beneath and support the instep portion of the foot and the other of which is to engage the opposite side portion of the instep or arch portion of the foot and prevent spreading of this portion of the foot. It will thus be seen that these supporting and bracing wings 3 will serve to support and brace the foot. An auxiliary inner sole section 4 which is shown

in Figs. 9 and 10 is to be put in place beneath the instep and heel portion of the insole 1 where it will be secured at its forward end to the underface of the insole with the channels 5 of this section registering with the end portion of the channel 2 of the insole. In order to brace the insole, there has been provided a bracing plate 6 which is formed of sheet metal and is shaped as shown in Figs. 2 and 3 to fit into the shoe beneath the insole and upon the auxiliary insole section 4. This bracing plate is provided at one end with an opening 7 to receive a fastener 8 which will pass downwardly into the heel as shown in Fig. 1 and the other end portion of the plate has been provided with spurs 9 which will engage the forward end of an arch pad. A side wing 10 is provided at one side of the plate and

will extend upwardly beneath the side wing 110

3 at that side of the insole so that this side wing will be supported and prevented from having any tendency toward moving outwardly of the shoe in a transverse direction. 5 The forward edge portion of this plate is tapered as shown clearly in Fig. 3 so that when the bracing plate is put in place, it will fit properly between the insole and auxiliary insole portion without making a rough place 10 in the shoe. In order to force the instep portion of the foot upwardly and support it in this position so that a fallen arch will be corrected, there has been provided a pad 11 which is shaped as shown in Figs. 4, 5 and 15 6. This pad in top plan conforms to the contour of the instep portion of the insole and is provided with an upper surface which is curved longitudinally as shown in Fig. 4 and formed concave in cross section or end 20 elevation as shown in Fig. 6. By having the pad shaped as shown, it will be provided with side portions which serve to prevent spreading of the instep portion of the foot and this pad will further be curved longitudinally so that the instep will be properly 25 molded longitudinally. It will thus be seen that this construction will provide an inner sole and arch support construction which will cause proper molding of the foot and 30 bracing and supporting of the foot in the proper shape so that a case of fallen arch may be corrected.

I claim:

1. In a shoe construction, an insole having 35 its instep portion provided with side wings extended upwardly, a rigid plate beneath the instep and heel portion of said insole and having a side wing extending beneath a side wing of said insole, fastener means for the 40 rear end portion of said plate, and an arch pad between said plate and the instep portion of said insole having its upper face convexed longitudinally and concaved transversely.
- 45 2. In a shoe construction, a main insole having its instep portion provided with side wings extending longitudinally and pro-

jected upwardly, an auxiliary insole beneath the heel and instep portion of said main insole and having its forward end portion secured to the main insole, a rigid plate between the main and auxiliary insoles and anchored to the auxiliary insole and having a side wing projecting upwardly along the instep portion of the main insole, and an arch pad between said plate and the instep portion of said main insole. 50

3. In a shoe construction, a main insole, an auxiliary insole secured at its forward end to the underface of said main insole adjacent the forward end of the instep portion thereof and extending rearwardly beneath the instep and heel portions of said main insole, a rigid plate between the auxiliary and main insoles and anchored to said auxiliary insole, 65 and an arch pad between said plate and the instep portion of said main insole. 70

4. The structure of claim 3 having the arch pad provided with flared end portions and having its upper face convexed longitudinally to provide feathered end portions and concaved in cross section. 75

5. In a shoe construction, an insole, an auxiliary insole portion secured to said insole adjacent the instep portion and extending rearwardly beneath the instep and heel portion of the main insole, said main insole having its instep portion provided with flaring side wings extending upwardly, a rigid plate positioned between the main and auxiliary insoles and extending along the instep portion and overlying the forward end of the heel portion of the auxiliary insole, fastener means for the rear end portion of said plate, said plate having one side provided with a side wing extending beneath the side wing at the corresponding side of said main insole, and an arch pad upon said plate and beneath the instep portion of said main insole and having its upper face transversely 85 concaved and longitudinally convexed. 90

In testimony whereof I hereunto affix my signature.

MILES B. COOPER.
